OF NEW YORK.

PICTURE-FRAME STABILIZER.

1,177,106.

Specification of Letters Patent. Patented Mar. 28, 1916.

Application filed March 16, 1915. Serial No. 14,792.

To all whom it may concern:

Be it known that we, GEORGE X. HICKERSON, a citizen of the United States, residing at Brooklyn, in the county of Kings and State of New York, and GEORGE C. HEMENWAY, a citizen of the United States, residing at New York, in the county of New York and State of New York, have invented certain new and useful Improvements in Picture-Frame Stabilizers; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention has reference, generally, to a picture-frame stabilizer; and the invention relates, more particularly, to a simple device for attachment to picture-frames and the like adapted to fixe the same, when suspended or hung upon a wall, in a true straight position and maintain the same against swinging or moving out of such straight position.

The invention has for its principal object to provide a very simple, cheap, easily made and easily applied device of the kind and for the purposes above-mentioned, and which provides a novel and efficient picture-frame stabilizer.

Another object of the present invention is to provide a construction of picture-frame stabilizer which possesses a requisite degree of resiliency sufficient to accomplish a shock absorbing effect when the same is in use, so that jars, tremors or vibrations of the wall or picture-frame will not tend to disconnect the novel stabilizer from its operative relation either to the wall or picture-frame.

Other objects of the present invention, not at this time more particularly enumerated, will be clearly understood from the following detailed description of the same.

With the various objects of the present invention in view, the same consists, primarily, in the novel construction of picture-frame stabilizer hereinafter set forth; and the invention consists, furthermore, in the novel arrangements and combinations of the several devices and parts, as well as in the details of the construction of the same, all of

which will be more fully described in detail in the following specification, and then finally embodied in the claims which are appended to and which form an essential part of said specification.

The invention is clearly illustrated in the accompanying drawings, in which:

Figure 1 represents a suspended picture and frame, the latter being equipped with the novel picture-frame stabilizer made according to and embodying the principles of the present invention. Fig. 2 is an enlarged vertical cross section of the same, taken on line 2—2 in said Fig. 1. Fig. 3 is a detail face view of the novel picture-frame stabilizer; Fig. 4 is an edge view of the same; and Fig. 5 is a vertical cross section of the same, taken on line 5—5 in said Fig. 3. Fig. 6 is a detail face view of a slightly modified construction of the novel picture-frame stabilizer; and Fig. 7 is a vertical cross-section of the same, taken on line 7—7 in said Fig. 6. Fig. 8 is another slightly modified construction of the novel picture-frame stabilizer.

Similar characters of reference are employed in the hereinabove described views, to indicate corresponding parts.

Referring now to the said drawings, the reference character 1 indicates a picture and picture-frame, suspended by a supporting wire 2 or any other suitable supporting means, from a wall-hook 3 connected with the wall 4.

The reference character 5 indicates the complete picture-frame stabilizer made according to and embodying the principles of the present invention, the same preferably comprising a main-body consisting of a pair of disk-like elements 6 and 7 connected together by a neck-piece 8. Said main-body is adapted to be folded over at its neck-piece or doubled back upon itself so that the respective disk-like elements 6 and 7 are alined one with the other, and preferably separated one from the other by a slight intervening space 9. Preferably struck up out of said disk-like element 6, so as to be integrally formed in connection therewith, is an outwardly extending pin-shank 10, sharpened at its free end to provide a piercing-point 11; and, in like manner, preferably struck up out of said disk-like element 7, so as to be integrally formed in connection therewith, is an outwardly ex-

tending pin-shank 12, sharpened at its free end to provide a piercing-point 13. While it is preferable to form said respective pin-shanks 10 and 12 integrally with said main body or its disk-like elements, it must be understood that the same may be formed of separate pieces and secured to said main body or its disk-like elements in any suitable manner, or by any suitable means.

10 In applying the novel construction of picture-frame stabilizer to its use, the same is arranged as follows:—One of the pin-shanks, as for example the pin-shank 10, is forced into the back of the picture-frame 1 at its lower end, and in a location substantially midway between the side ends of the picture-frame, the pin-shank 10 being buried in the picture-frame until the disk-like element 6, from which said pin-shank 10 projects, rests against the picture-frame. The picture-frame 1 is then suspended from the wall-hook 3 by its supporting wire 2, or other supporting device, and adjusted so that the same hangs in proper straight alignment on the wall 4. Then by pressing the lower end of the picture-frame 1 toward the wall 4, the oppositely extending pin-shank 12 which projects from the disk-like element 7 is thereby forced into the wall 4 until said disk-like element 7 rests against the said wall. In this manner the lower end of the picture-frame 1 is secured to the wall and thus fixed against lateral swaying or swinging out of its proper straight alignment on the wall. The use and application of the novel stabilizer does not prevent or interfere with any desired forward tilting of the upper end of the picture-frame 1. It will also be apparent that the main-body of the stabilizer, being interposed between the wall 4 and the lower edge of the picture-frame 1, thereby maintains the latter spaced slightly away from the former so that dust collecting on the back of the picture-frame can fall from the same through said space. Since the two disk-like elements 6 and 7, when alined one with the other and slightly spaced apart, are connected at a small portion of their periphery by the comparatively narrow neck-piece 8, it follows that a certain amount of resiliency or free vibratory movement is established between the disk-like elements 6 and 7, which provides a shock-absorbing effect, so that vibrations or any oscillating tendency of the picture-frame, due to vibration in the walls of the building, wind, or other causes, are absorbed by the resiliency of the stabilizer so that any tendency of the pin-shanks to loosen their hold, either in the wall 4 or picture-frame 1 is counteracted and eliminated.

Referring now to Figs. 6 and 7 of the accompanying drawings, we have illustrated therein a slightly modified construction of

the novel picture-frame stabilizer made according to and embodying the principles of our present invention. In this modified construction we provide the alined and spaced apart disk-like elements 14 and 15, from which project respectively in opposite directions the sharpened pin-shanks 16 and 17. Interposed between said disk-like elements 14 and 15 is a resilient-pad 18, preferably made of felt, or any other suitable material providing the requisite degree of resiliency. A suitable marginal beading 19, surrounds and overlaps the respective marginal edges of said disk-like elements 14 and 15, so as to secure said resilient-pad against accidental removal from operative position between said disk-like elements. The disk-like elements 14 and 15 may be joined together at a portion of their respective peripheries by the integral neck-piece 8, but if desired said neck-piece 8 may be omitted, as shown in Fig. 8 of the drawings, since the pad retaining beading 19 will serve not only to hold said resilient-pad 18 against removal, but also to maintain said disk-like elements in proper assembled and registered relation one with the other. The manner of applying and using this modified construction of picture-frame stabilizer is the same as already above-described. The resilient-pad 18 acts as a buffer or shock-absorber against vibrations of the wall or picture which are transmitted to the disk-like elements 14 and 15. This modified construction of stabilizer is particularly useful in connection with very heavy picture-frames, the weight of which would tend to close together and so maintain the disk-like elements if no interfering buffer were used, so that the resilient effect of the same would be thus impaired.

In the case of a large picture-frame, instead of securing one stabilizer thereto in the manner and location shown, and above described, one may be placed at each lower outer corner of the picture-frame.

It will be readily understood from the above description that our present invention provides a very handy, convenient and easily applied picture-frame stabilizer of simple and cheap construction, and of efficient operation.

We are aware that some changes may be made in the arrangements and combinations of the various devices and parts, as well as in the details of the construction of the same, without departing from the scope of the present invention as set forth in the foregoing specification, and shown in the accompanying drawings. Hence, we do not limit our invention to the exact arrangements and combinations of the parts as described in the foregoing specification and as illustrated in the accompanying drawings, nor do we confine ourselves to the ex-

act details of the construction of the said parts.

We claim:—

- 5 1. A picture-frame stabilizer comprising a main body consisting of a pair of disk-like elements, a comparatively narrow neck-piece by means of which said disk-like elements are joined together, said main-body being doubled over at its neck-piece to aline said
- 10 10 disk-like elements one with the other, and a sharpened pin-shank extending outwardly from each disk-like element.

- 15 2. A picture-frame stabilizer comprising a pair of alined disk-like elements and spaced slightly apart, each disk-like element having an outwardly projecting sharpened pin-shank, a resilient pad inserted between said disk-like elements, and means for re-

taining said resilient pad in such connection.

20

3. A picture-frame stabilizer comprising a main-body doubled upon itself to provide a pair of connected disk-like elements capable of a resilient movement toward and away from each other, and sharpened pin-shanks extending outwardly from each disk-like element.

In testimony, that we claim the invention set forth above we have hereunto set our hands this 12th day of March, 1915.
